Samuel J. Goldfarb, New York, N. Y.

Application April 22, 1949, Serial No. 2,190

Term of patent 3½ years

(Cl. D3—26)

To all whom it may concern:

Be it known that I, Samuel J. Goldfarb, a citizen of the United States, residing at New York, in the county of New York and State of New York, have invented a new, original, and ornamental Design for a Dress, of which the following is a specification, reference being had to the accompanying drawing, forming a part thereof.

In the drawing:

Fig. 1 is a front elevational view of a dress, showing my new design;

Fig. 2 is a rear elevational view of the same; and

Fig. 3 is a front elevational view of the dress, fully opened.

I claim:

The ornamental design for a dress, as shown.
SAMUEL J. GOLDFARB.
